APPARATUS FOR GRINDING LENSES

George A. Clement, Mount Vernon, N. Y., assignor
to General Optical Company, Inc., Mount Ver-
non, N. Y., a corporation of New York

Application June 27, 1947, Serial No. 757,626

3 Claims. (Cl. 51—131)

1

This invention relates to the art of lens grinding, particularly ophthalmic or spectacle lenses. While the invention is applicable to both single and multiple vision lenses, it has a special utility in connection with bifocal lenses and will be described and explained as it is applied in the production of such lenses, especially of the meniscus type.

Fused bifocal lenses very generally have the reading insert or segment fused into a recess on the plus or convex side, and it is common commercial practice for the manufacturer of the blanks to finish this bifocal or plus side of the blank to the final optical surface on one of the standard base curves. Such blanks are said to be semi-finished and the grinding and polishing of the surface on the other or minus side of the blank to satisfy the prescription is subsequently done. The blanks are commonly circular in form.

The optical center of the finished lens, in the case of bifocals especially, is commonly displaced from the geometric center of the blank, ordinarily being located below the horizontal meridian of the blank and to one side of the vertical meridian so as to set in the reading segment of the final lens somewhat. The location of the optical center of the finished lens, being upon the axis of the lens, depends, of course, upon the disposition of the centers of the two surfaces and hence upon the attitude of the blank with respect to the grinding axis during the generation of the prescription curvature. The axis of the lens is that intersecting line which includes the spherical centers of the two surfaces, and in spherical lenses is the only line of observation which is free from prism.

As is well known, the common procedure in the generation of the prescription surface is to mark a spot on the finished surface to denote the location of the optical center, and then to chip or break off the edge of the blank in one or both meridians to bring the center equidistant from the ends of the meridians. At that stage, the edge of the blank is of uneven thickness at the ends of the meridians, and it is necessary to present the blank to the grinding tool in the subsequent grinding of the prescription or minus side so that the edge of the blank becomes of even thickness at the four points corresponding to the ends of the meridians. This requires localizing of the grinding pressure and frequent removal of the blank and measuring of the thickness at the meridian ends with calipers.

2

Such procedure is manifestly very slow and not only involves the loss of time due to the frequent removal and measuring of the blank during the generating process, but also the danger of damaging the finished surface due to the fine particles of glass which result from the chipping or crumbing, as it is called, adhering to that surface and scratching it, and there is also the danger of the lens flying off the grinding tool and breaking in this operation.

The present invention aims to improve on this procedure. The need for chipping or crumbing the edges of the blank before grinding the second side is eliminated, as is the need for measuring the edge thickness as the grinding progresses. The invention includes means for definitely and accurately locating the blank with respect to the grinding tool and retaining it in that relative position until the generating operation is finished.

In accordance with the invention, the semi-finished blank is mounted on a rotative holder the axis of which includes the spherical or generating center of the grinding tool, and which has a supporting or locating spherical surface concentric with the finished surface of the blank, and adjusting the blank on that surface until the radius of the finished surface that coincides with the desired optical center is brought into the axis of the holder. The blank is then secured in this adjusted position and the grinding proceeds until the surface on the minus side is generated. The common radial line of the two surfaces, which, as explained in my prior Patent No. 1,467,308, is the line that determines the axis of the finished lens, is in this case also the axis of generation.

The invention also includes special apparatus to carry out the method described. Preferably and most conveniently, the holder has a marker, preferably in the form of an axial post, in the center of the spherical locating surface to denote the axis of rotation, and the blank is fixedly mounted on a ring which rests on the spherical surface of the holder with the finished surface of the blank toward the holder. The axis of the ring, therefore, includes the spherical center of the finished surface, and adjustment of the ring adjusts the blank about that center. Means are provided to clamp the ring on the holder in adjusted position.

The invention not only saves time and greatly facilitates the operation in the generation of the prescription surface on the desired axis, as has been pointed out, but it minimizes the skill and

experience required to perform the operation successfully. The invention has other advantages and novel features which will appear from the particular description of the embodiment illustrated in the drawings, which embodiment will now be described and the invention will thereafter be pointed out in claims.

Fig. 1 is a section on enlarged scale of a standard, fused bifocal, semi-finished blank.

Fig. 2 is a face view of the same with the location of the desired optical center indicated.

Fig. 3 is a diagrammatic view illustrating the problem in connection with a sectional diagram of the blank.

Fig. 4 is a similar diagrammatic view with a diagrammatic representation of portions of apparatus associated therewith to show a simple solution of the problem.

Fig. 5 shows diagrammatically a section of a ring and of a blank secured therein, with the problem indicated.

Fig. 6 is a diagrammatic view showing the elements of Fig. 5 mounted in operative relation with respect to a holder and grinder.

Fig. 7 is a section on the same enlarged scale of the complete mounting apparatus with a blank therein, the plane of the section being indicated by line 7-7 of Fig. 8.

Fig. 8 is a plan of the apparatus on reduced scale.

Fig. 9 is a plan of the ring.

Fig. 10 is an exploded view in side elevation of the three members of the apparatus, to wit, the ring, the chuck in which the ring is clamped and the holder in which the chuck is clamped.

A typical fused bifocal lens blank is shown in Figs. 1 and 2 in substantially double the normal size. The major blank member 1 is of crown or similar optical glass of a relatively lower index of refraction, while the minor blank member or segment 2 of glass having a higher index of refraction is fused into a spherical recess formed in the plus or convex side of the blank. To produce the semi-finished blank, this side, which is known as the bifocal side, is first ground and polished to a finished optical surface 3 of a selected base curve. It is to the grinding or generating of the prescribed curve on the second or minus side of the blank that this invention relates.

The meniscus, semi-finished blank has a molded, rough surface 4 on its concave or minus side, which, as shown, may be spherical and have its center of curvature on the geometrical central radius of the finished surface 3. Fig. 3 so shows it. The radial line 5 intersects the geometrical central point o of the surface 3 and also the spherical center 6 of the surface 3 and the spherical center 7 of the rough surface 4. In other words, both surfaces of the semi-finished blank are shown as symmetrical about the line 5.

It will now be assumed that it is desired to have the optical center of the finished lens located on a radius including the point x instead of the point o of the surface 3. Then the radial line 8 becomes the axis of the lens and must, of course, include the center 6 and the spherical center 9 of the surface 10 that is to be formed on the minus side of the blank. The final lens may be cut from the finished lens blank in any desired shape, for example, in the outline indicated by the dot and dash line in the plan view.

To accomplish the generation of the surface 10, the holder is rotated about an axis that includes the line 8. The simple diagram of Fig. 4

illustrates this. It is assumed that a holder 11 is rotatable about the axis of the post 12 which acts as a marker or indicator, and that the holder 11 has on its upper face an integral ring 13 coaxial with 12 and of uniform height. The spherical grinding tool 14 has its generating center on the axis of post 12 which is the axis of rotation, in this case at the point 9, the curvature of the tool being such as to generate the surface 10.

The blank is placed on the ring 13 with its surface 3 down. The axis of the ring therefore includes the center 6 and sliding of the blank on the ring adjusts it about the center 6. Hence the radius of the surface 3 which intersects the point on the surface that happens to be in the axis of the post 12, is the radius that corresponds to the axis of the finished lens and includes the optical center.

In Fig. 4, for example, the blank is disposed on the ring so that the radius 8, which intersects point x, is in the axis of the post 12, that is, the axis of rotation of the holder 11. The line 8 is, therefore, the radial line that includes the optical center. To put it simply, what is done is to place the point x, which in practice will be designated by a dot made on the surface 3, directly over the end of the post 12, and with the blank secured in that position, the rotation of the holder and hence of the blank, with the minus side of the blank in contact with grinder 14, will generate the surface 10 with the centers 9 and 6 in line 8 which is the axis of rotation.

It is obvious that in lieu of sliding the blank on a ring to get the desired optical center over post 12, it might slide in and be governed by a complementary concave surface in the holder. That, in effect, is what is done in practice. Figs. 5 and 6 show diagrammatically this feature of the commercial apparatus.

The blank 1 is mounted in a ring 15. In this case, the blank fits in the ring and is not adjustable with respect to it. This assembly of ring and blank is adjustably disposed on the holder 11, which, in this case, has a concave spherical face 16 symmetrical about the post 12. This surface is concentric with the surface 3, its radius 17 being equal to the radius 18 of surface 3 plus substantially the height of the ring 15.

Hence, when the ring slides on the surface 16, it slides about 6 as a center, and the blank therefore slides about 6 as a center, as is the case in Fig. 4. So all that it is necessary to do to get the desired location of the optical center of the finished lens, is to adjust the ring 15 until the point x comes over the post 12, lock the ring with screws 19, one of which is shown, and grind. In practice the generating tool 14 is itself also rotated on the axis 20, the tool being of a size to extend at least from the edge of the blank across the center of rotation of the blank in all angular positions of the blank, in order to prevent the formation of rings in the surface being ground.

In Figs. 7 to 10, inclusive, is shown the actual apparatus being used commercially. In addition to the ring and the element heretofore designated as holder, the apparatus includes a third element, termed a chuck which acts as the positioning holder for the ring. The advantage of having this third element is that it makes for easy replacement or substitution when a change occurs in the base curve of the blanks being ground.

The holder in this construction consists of a base member 21 that is mounted on a rotative

spindle 22 and is attached thereto by a set screw 23. A chuck member 24 rests upon and is clamped to the holder 21, and it is the chuck that carries the axial post 12. The chuck has a machined bottom surface that rests upon three studs 25 on the top face of the holder, the studs being precisely machined to receive and hold the chuck in coaxial relation to the spindle.

The chuck is a cylindrical member and is clamped and positioned by three arcuate segments 26 upstanding from the peripheral edge of the holder. The middle portion of one of these segments, which, as in the other two, extends higher than the rest of the segment, is pivoted, as shown in Fig. 7, and is urged out by a spring 27 and is forced in by a screw 28 engaging in a tapped hole in the holder and operated by a handle 29. These parts are all designed and machined so that when the segments 26 are tightened the post 12 is in exact axial alignment with the spindle.

The chuck 24 is itself cup shaped and has a removable and replaceable circular bottom member 30, the surface 16 of which is a segment of a sphere concentric with the surface 3 of the blank. This surface 16 acts as the guide for the blank holding ring, as explained in connection with Fig. 6. The removability of the bottom member 30 permits of change of this member to keep the surface 16 in agreement with the surface 3 when blanks having different base curves are being treated.

The ring member 31 rests on the surface 16 and is secured in the chuck 24 in adjusted position. For this purpose the chuck is provided with three arcuate segments 32 upstanding from its peripheral edge, through each of which is tapped an adjusting screw, two of which, numbered 33, have knurled heads, while the third screw, numbered 34, has a flat head and is a thumb screw to be set up tightly to serve as the final lock for the ring.

The ring is a cup shaped member having a central opening in its bottom, and has a sharp axial lip 35 on its bottom face which rests upon the surface 16 and sharply defines the plane of contact. A removable annular member 36 fits in the ring and has a sharp top edge on which the blank rests. The ring has three upstanding arcuate segments for receiving and clamping the blank. Two of these, numbered 37, are integral with the top edge of the ring, while the third, numbered 38, is pivoted in a housing extension 39 on the ring and is controlled by a set screw 40 tapped through the housing and bearing against the member 38. A spring 41 urges the member 38 outwardly on its pivot so that the clamps open up as the screw is retracted. The segments 37 and 38 are faced with arcuate pads 42 of leather, fiber or the like to protect the edge of the blank when the clamps are tightened.

In use, a chuck member is chosen the bottom member 30 of which has a surface 16 of proper curvature to be concentric with the surface 3 of the blank to be treated. The point *x* is marked on the surface 3 and the blank is secured in the ring. The ring is then set in the chuck and adjusted over the surface 16 until the point *x* is in register with the small axial extension of the post 12. The screws 33 and 34 are then set up and the ring is thereby locked in the adjusted position. The grinding may then proceed until the surface 10 is generated. Thus the axis of the finished lens is made to include the point *x*.

While, as a rough measure, the radius 17 is 75

said to be equal to the radius 18 plus the height of the ring, strictly the amount by which the radius 17 exceeds the radius 18 in length is a function of the effective height of the ring, that is, of the axial distance from the plane of contact of the lip 35 with the surface 16 to the plane of contact of the surface 3 with the sharp edge of the member 36 on which the blank rests.

The grinder 14 is shown as having an annular spherical grinding surface. As is well known, the annulus may be diminished in width until it becomes so narrow that the contact area is no more in effect than a circular line. The axis will, of course, always include the center 9, which will be the spherical center of the surface generated by the grinder. It will be understood, therefore, that the term spherical herein when applied to the grinder, is intended to comprehend an annular tool of any width, and the terms spherical center and generating center as applied to the grinder, are intended to comprehend the point of intersection of the axis of the tool with the axis of generation, that is, the spherical center of the surface generated thereby.

It will also be understood that while in the above description reference has been made only to the generation of spherical surfaces on the minus side, the method and apparatus are equally applicable to the production of toric surfaces, and that the mounting of the blank is the same whether or not a cylindrical axis is introduced.

It is obvious that the method may be performed by apparatus differing in detail from that shown in the drawings and above particularly described, and that the invention is not limited to such details but only as pointed out in the following claims.

What is claimed is:

1. A mechanism for generating a surface on the minus side of a meniscus lens blank finished on the plus side, comprising a rotative spindle, a holder mounted upon and rotative with said spindle, a removable chuck secured to the holder and having a concave spherical surface the spherical center of which is disposed on the axis of rotation of the holder, a ring adjustably disposed on said chuck surface, means to secure a lens blank on said ring with the plus side resting on the ring, means to secure the ring in adjusted position, the spherical center of the chuck surface being substantially beyond the supporting edge of the ring, and a rotative annular grinding tool applicable to the minus side of the blank and having its axis of rotation intersecting the axis of rotation of the holder.

2. A mechanism for generating a surface on the minus side of a meniscus lens blank finished on the plus side, comprising a rotative spindle, a holder mounted upon and rotative with said spindle, a removable chuck secured to the holder and having a concave spherical surface the spherical center of which is disposed on the axis of rotation of the holder, a ring adjustably disposed on said chuck surface having its ends in parallel planes normal to its axis, an axial post extending from the chuck surface and into the ring, means to secure a lens blank on said ring with the plus side resting on the ring, means to secure the ring in adjusted position, the spherical center of the chuck surface being substantially beyond the supporting edge of the ring, and a rotative annular grinding tool applicable to the minus side of the blank and having its axis of rotation intersecting the axis of rotation of the holder.

6. A mechanism for generating a surface on the minus side of a meniscus lens blank finished on the plus side, comprising a rotative spindle, a holder mounted upon and rotative with said spindle, a removable chuck secured to the holder and having a concave spherical surface the spherical center of which is disposed on the axis of rotation of the holder, a ring adjustably disposed on said chuck surface having its ends in parallel planes normal to its axis, an axial post extending from the chuck surface and into the ring, means to secure a lens blank on said ring with the plus side resting on the ring, means to secure the ring in adjusted position, the spherical center of the chuck surface being substantially beyond the supporting edge of the ring, and a rotative annular grinding tool applicable to the minus side of the blank and having its axis of rotation intersecting the axis of rotation of the holder.

3. A mechanism for generating a surface on the minus side of a meniscus lens blank finished on the plus side, comprising a rotative spindle, a holder mounted upon and rotative with said spindle, the holder having thereon a concave spherical surface the spherical center of which is disposed on the axis of rotation of the holder, a ring having its ends parallel and normal to its axis and disposed on the said concave surface so as to be universally adjustable thereon, means to secure the ring in adjusted position on said surface, means to secure a lens blank on said ring with the plus side resting on the ring, the spherical center of the concave spherical surface on the holder being substantially beyond the supporting edge of the ring, and a rotative grinding tool applicable to the minus side of the blank and designed to grind a surface also centered on the axis of rotation.
